SIGN SUPPORT BRACKET

Joe D. Huffman, Tulsa, Okla., assignor to Continental Research Company, Inc., Tulsa, Okla., a corporation of Oklahoma

Filed Oct. 13, 1966, Ser. No. 4,264

Term of patent 14 years

(Cl. D54—1)

FIG. 1

FIG. 2

FIG. 3

The fragmentary broken line representation of a support pole and a second bracket in FIGURE 4 is for purposes of illustration only.

I claim:

The ornamental design for a sign support bracket, substantially as shown and described.
